J. C. JORDAN, OF WATERTOWN, WISCONSIN.

Letters Patent No. 70,857, dated November 12, 1867.

COMPOUND TOOL FOR PUNCHING AND SHEARING.

The Schedule referred to in these Letters Patent and making part of the same.

TO ALL WHOM IT MAY CONCERN:

Be it known that I, J. C. JORDAN, of Watertown, in the county of Jefferson, and State of Wisconsin, have invented a new and improved Combined Punch and Shears; and I do hereby declare that the following is a full, clear, and exact description thereof, which will enable others skilled in the art to make and use the same, reference being had to the accompanying drawings, forming part of this specification, in which—

Figure 1 is a side elevation, partly in section, of my improved punch and shears.

Figure 2 is a front elevation of the same.

Similar letters of reference indicate like parts.

This invention relates to a machine wherein sheet and bar iron and other metals can be cut or punched, as may be desired; and the invention consists in so shaping the main lever of the machine that it will at the same time force down a punch by a cam, and operate the shears, one of the blades of which is secured to the said lever.

A represents the frame of the machine, which can be made of cast iron or other suitable metal or material. It rests upon four (more or less) supports or feet, b, and is formed of three portions, c, d, and e, which may be cast together in one piece, or be made in distinct pieces bolted or secured together in any suitable manner. The portion c forms the standard for the punch, being bent in the usual manner, so that the upper arm will serve as a guide for the punch or mandrel, and the lower arm will form the bed, on which the die f is secured. The portion d is an arm projecting from the front of the frame, and holding the lower or stationary blade B of the shears, which is secured to it by means of bolts, or in any other suitable manner. The portion e is the frame for supporting the working mechanism of the machine. C is a lever, pivoted to the frame A, near to its front and nearly above the line of the punch, or level with the shears, by a pin, g. The rear or long arm of the lever C is provided with a toothed segment, D, which meshes into a pinion, E, that is mounted on a pin, h, as shown. A plate, i, the upper and lower ends of which are firmly secured to the frame A, serves as a support for one end of the pin g, and a similar plate, K, supports or forms a bearing for the axle of the pinion E. A handle, F, is secured to the pinion, and by working it up and down the lever C will be oscillated. At the front end of the lever C is arranged a lip, l, which serves to hold the upper movable blade G of the shears, and which stands in such a relation to the part d of the frame A, that by oscillating the lever C the cutting edges of the blades B and G will be brought towards each other, and well-working shears are thus provided. The lower portion H of the front arm of the lever C is made in the form of a cam, as shown, and its lower surface touches the upper end of the mandrel I, which slides in a box, L, that is provided in the frame A. When the long arm of the lever C is raised, the short arm will be lowered, and the cam H will force the mandrel down, and with it the punch M, which is held in the mandrel by any suitable device. The cam H is connected with the mandrel by means of a plate or plates, m, whereby the latter is raised with the cam as soon as the long arm of the lever C is depressed.

Thus the punch and shears can be worked at the same time in this apparatus, and one machine is made to perform the same work for which two were used heretofore, or where at least two sets of tools were heretofore used, one of which only could be used or applied at the same time.

What I claim as new, and desire to secure by Letters Patent, is—

The combination of the frame A, lever C, cogged segment D, pinion E, handle F, shears B G, cam H, box L, mandrel I, punch M, and die f, all arranged and operating substantially as herein described and represented.

J. C. JORDAN.
